UNITED STATES PATENT OFFICE.

ABRAHAM BIENENZUCHT, OF NEW YORK, N. Y.

BUCKLE.

940,498.

Specification of Letters Patent. Patented Nov. 16, 1909.

Application filed November 6, 1908. Serial No. 461,305.

To all whom it may concern:

Be it known that I, ABRAHAM BIENENZUCHT, a citizen of the United States, and a resident of the city of New York, borough of Manhattan, in the county and State of New York, have invented a new and Improved Buckle, of which the following is a full, clear, and exact description.

The object of the invention is to provide 10 a new and improved buckle, more especially designed for use on men's trousers belts, and arranged with a particularly shaped hook on the tongue, for engagement with the fastening device used for closing the flies of the 15 trousers, to hold the belt against upward movement on the trousers.

The invention consists of novel features 20 and parts and combinations of the same, which will be more fully described herein- after and then pointed out in the claims.

A practical embodiment of the invention 25 is represented in the accompanying drawings forming a part of this specification, in which similar characters of reference indicate corresponding parts in all the views.

Figure 1 is a rear face view of the buckle; Fig. 2 is a sectional plan view of the same on the line 2—2 of Fig. 1; and Fig. 3 is a cross section of the improvement as applied.

30 On the buckle frame A is pivoted the tongue B, provided with an integral hook C adapted to hook onto a button D or other fastening device employed for closing the upper ends of the flies E, E of the trousers.

35 The buckle is attached to one end of the belt F adapted to encircle the trousers at the waist, the free end of the belt being fastened in place by the buckle in the usual manner.

The hook C is preferably approximately 40 U-shape, having an attaching arm C' depending from the tongue B, at a point between the ends of the tongue, and from the lower end of the arm C' extends inwardly and rearwardly the connecting bar C², from the free end of which rises the terminal arm C³ enlarged at its free end, the connecting bar C² and the terminal arm C³ being opposite the space inclosed by the buckle frame. Now by the oblique position of the hook C

45 relatively to the tongue B and frame A, the hook can be readily passed between the flies E, E and moved upward, to hook onto the shank of the button, as plainly shown in

Figs. 1 and 3, so that the buckle is held against further upward or sidewise movement when the belt is buckled up. The enlarged end of the arm C³ prevents the arm from catching in the flies when passed between the same, and when the belt is buckled up the enlarged end of the arm by engaging 55 the shank of the button assists in holding the buckle in position. By arranging the hook on the tongue, it is evident that when the belt is buckled up, the tongue B is held closed on the frame A, and hence the 60 hook cannot accidentally slip out of engagement with the button D or like fastening device.

Having thus described my invention, I claim as new and desire to secure by Letters 70 Patent:

1. A buckle provided on its tongue between the ends thereof with a hook rigidly attached to the tongue, the free end of the hook extending upward.

2. A buckle comprising a buckle frame, a tongue pivoted thereon, and a hook integral with said tongue and approximately U-shaped and standing obliquely to the tongue.

3. A buckle comprising a buckle frame, a tongue pivoted thereon, and a hook integral with said tongue and approximately U-shaped and standing obliquely to the tongue, one arm of the hook extending downward from the tongue, the connecting bar of the hook extending inwardly and rearwardly and the other hook arm rising from the free end of the connecting bar.

4. A buckle provided with a hook having an arm rigidly connected with a member of the buckle between the ends of the latter, an inclined connecting bar extending from said arm in direction of one end of the buckle, and a hook arm extending laterally from the end of the connecting bar, the free end of the hook arm being enlarged, the connecting bar and said hook arm being at the rear of the buckle and opposite the space inclosed by the buckle frame.

In testimony whereof I have signed my 100 name to this specification in the presence of two subscribing witnesses.

ABRAHAM BIENENZUCHT.
